United States Patent Office.

EDWARD H. HART, OF NEW YORK, N. Y.

Letters Patent No. 77,488; dated May 5, 1868.

IMPROVEMENT IN FUR CUFFS.

The Schedule referred to in these Letters Patent and making part of the same.

TO ALL WHOM IT MAY CONCERN:

Be it known that I, EDWARD H. HART, of the city, county, and State of New York, have invented a new and useful Improvement in Cuffs; and I do hereby declare that the following is a full, clear, and exact description thereof, which will enable others skilled in the art to make and use the same, reference being had to the accompanying drawings, forming part of this specification.

This invention relates more particularly to that portion of wearing-apparel commonly called "cuffs," and which are usually made of fur skins, either in whole or part. It is applicable also to leggings, whether of fur or leather.

The invention consists in securing together the two ends of the fur, silk, or other strip of which a cuff is made, so that the ends overlap by means of an India-rubber or other elastic band or cord, so applied as to be covered by the ends of the cuff, when the overlapping end is fastened down by means of an elastic or any other suitable fastening properly attached to the two ends. A modification of this invention consists in bringing the ends together by means of the elastic connection without overlapping.

By means of the elastic connection between the ends of a cuff, the cuff is enabled to be freely drawn over the hand into position upon the wrist, and when brought there, held with sufficient firmness to prevent any accidental detachment as it is worn, the elastic band or connection allowing the cuff to yield, without injury to the material of which it is composed. In the accompanying plate of drawings my improvement in cuffs is illustrated—

Figure 1 being a perspective view of a cuff provided with an elastic connection according to the present invention.

Figures 2 and 3, sections taken through the cuff from one side to the other.

Similar letters of reference indicate corresponding parts.

A, in the drawings, represents the central portion of a cuff, which, in the present instance, is made of silk, having its edges or sides bound with fur strips, B, which are sewed or otherwise secured thereto.

D are the two ends to the cuff, and by means of an elastic band, E, secured at each end thereof to the cuff-strip A at e e, a short distance from each of its ends, whereby these ends are connected together, so as to overlap, the one upon the other; or the elastic connection E may be replaced by elastic threads or cords let into a hollow hem at each end of the fur or of the central strip, and secured at a short distance from the end, so as to hold the ends together.

F, an elastic fastening-strap, secured at one end to the end of the overlapping portion D; at its other, provided with an eyelet-hole, H, by means of which it can be set over and engaged with the headed stud I, secured in the overlapped portion or end, D, for the purpose of fastening the overlapping end down upon the cuff, and thus covering up or concealing from view the elastic-band connection.

When the elastic threads are used in place of the elastic-band connection E, the elastic fastening-strap serves to hold the two ends of the cuff lightly together.

From the above detail description of my improvement in cuffs, it is plainly obvious that the results hereinbefore stated are secured, and may be usefully applied to leggings, whether partially or wholly of fur, or leather, or other material.

Having described my invention, I claim as new, and desire to secure by Letters Patent—

A fur cuff, provided with a connecting elastic band, E, in combination with the elastic fastening-band F, the whole arranged substantially as shown and described.

The above specification of my invention signed by me, this fourth day of January, A. D. 1868.

EDWARD H. HART.
